UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

HOISTING MECHANISM

Application filed December 13, 1920, Serial No. 430,213. Renewed December 28, 1929.

My invention relates to hoisting mechanisms.

One of its objects is to provide an improved hoisting mechanism. Another object of my invention is to provide an improved hoisting mechanism having improved controlling mechanism. A further object of my invention is to provide an improved hoisting mechanism of the air driven type having improved mechanism for controlling the air driving means and its relation to the hoisting mechanism. Other objects and advantages of my improved construction will appear in the course of the following specification and appended claims.

In the accompanying drawings I have shown for purposes of illustration one form which my invention may assume in practice, together with certain modifications which may be resorted to if desired.

In these drawings,—

Fig. 1 is a view partially in side elevation and partially with the shell of the drum broken away to disclose details of the interior mechanism of my improved hoisting mechanism.

Fig. 2 is a central longitudinal vertical section through the axis of my improved hoisting mechanism.

Fig. 3 is a transverse section on the line 3—3 of Fig. 2.

Fig. 4 is a transverse section through the drum of my improved hoisting mechanism taken on the line 4—4 of Fig. 2.

Fig. 5 is a section taken on the line 5—5 of Fig. 4.

Fig. 6 is a view partially in elevation and partially in section on the line 6—6 of Fig. 4.

Figs. 7 and 8 are transverse sections 40 through the controlling valve, being taken respectively on the lines 7—7 and 8—8 of Fig. 2.

Fig. 9 is a transverse section taken on the line 9—9 of Fig. 5.

Fig. 10 is a similar section taken on the line 10—10 of Fig. 5, showing the arrangement of air passages.

Fig. 11 is a transverse section on the line 11—11 of Fig. 2 through the controlling valve.

Figs. 12 and 13 are fragmentary sections on planes similar to the plane of section of Fig. 2 and showing certain possible modifications of my improved construction.

In this illustrative embodiment, I have shown a winding drum 1 of usual construction journalized in suitable bearings 2 and rotatable about a central shaft 3, which extends longitudinally of the drum and with respect to which the drum is rotatable, this shaft being non-rotatably supported in suitable mountings 4, 4 and the parts being held in assembled relation by a clamping bolt 5 threaded into one end of the shaft 3, and the bearings 2 and supports 4 being carried by suitable arms 7 formed on any suitable support 8, herein in the form of a trunnion adapted to be adjustably mounted and clamped on a bar or otherwise in the same general manner as a drill.

Disposed in the drum 1 and positively connected thereto in a suitable manner is a hoist driving motor which in its general aspects resembles that constituting the invention of one George H. Gilman and forming the subject matter of application Ser. No. 332,519, filed October 22, 1919. This motor is enclosed within a suitable casing 9 arranged coaxially with the shaft 3 and rotatable relative thereto on suitable bearings 10 disposed at opposite ends of the casing. As shown, this casing houses a plurality of sets of rotors, one set being rotatable about a normally fixed gear and carrying with it the other set of rotors which themselves rotate, at a materially different (herein reduced) speed, and a rotatable gear fixedly connected to the drum, the construction being such that each set of rotors cooperates with the other not only in the rotation of the drum but in producing the speed reduction desired.

Referring more particularly to the drawings, in Figs. 2 and 4, it will be noted that a gear 11 is fixed to one end, herein the left hand end (Fig. 2) of the drum 1 and that this gear is rotatable, accordingly, with respect to the hollow shaft 3. Disposed radially about this gear 11 are a plurality of smaller gears or rotors 13 having a smaller number of teeth than the gear 11 and snugly housed in

suitable bosses 12 on the casing 9. These rotors 13 are herein each suitably splined as at 14 to suitable shafts 15 disposed longitudinally of the casing and journaled therein 5 in suitable bearings 16 at the opposite ends of the casing. Attention is herein directed to the fact that the shafts 15 are provided at points substantially midway between their ends with spacing flanges 17 and that they 10 carry, on the opposite sides of the flanges 17 from the rotors 13, another set of rotors 18, having a different number of teeth from that of gears 13, and similarly splined to the shafts. These gears 18 in turn mesh with a 15 gear 20 having a larger number of teeth than the gears 13 and 18 and journaled upon the shaft 3 as at 21, this gear being provided with a radially extending annular flange 22 whose end surface upon the side away from the 20 casing 9 is recessed and forms a housing having a perforated plate 23 carrying a plurality of cork inserts 24 whose purpose will hereinafter be explained.

From the foregoing description, it will be 25 readily understood that when suitable means is provided for effecting rotation of the gears 13 and 18 with respect to the gears 11 and 20, if the gear 20 be held stationary, the result will be rotation of the drum, but that if the 30 gear 20 be free to rotate, by reason of the load upon the drum there will be no rotation of the drum, but instead the gear 20 will rotate freely with respect to the shaft 3. For the purpose of maintaining the gear 20 stationary 35 when desired, I have arranged coaxially on the shaft 3 a sliding sleeve 25 provided with a radially extending flange 26 adapted to engage the cork inserts 24 and to force them into tight engagement with the flange 22. It 40 will be understood that the member 25 is keyed as indicated at 27 to the periphery of the shaft 3 whereby its rotation is prevented. To move the member 25 longitudinally I have formed in a sleeve 28 projecting toward the 45 right in Fig. 2 a series of threads 29 cooperating with a threaded sleeve 30, which is formed at its outer end with a spur gear 31 adapted to be engaged by a second spur gear 32, which latter is secured upon a shaft 33 50 journaled in the arm 7 and rotatable by a crank 34. Rotation of the crank 34 will obviously effect rotation of the gears 32 and 31 and by the interaction of the threaded sleeve 30 and thread 29 upon the sleeve 28, will 55 cause movement in opposite directions, depending upon the direction of rotation of the handle 34, of the clutch applying member 25. It will be understood that the sleeve 30 is 60 prevented from longitudinal movement by suitable means, herein by means of a shoulder 35 formed thereon. The annular flange 26 is provided with a suitable series of inserts of friction material 37 upon its side opposite the member 22 and these are adapted to engage the end plate 38 of the drum 1 upon

movement of the member 26 toward the right in Fig. 2, and by reason of the fact that at that moment the gear 20 is no longer positively held, the motor is unable to exert any torque upon the drum 1 and accordingly the 70 engagement of the frictional material 37 carried by a stationary flange 26 with the rotating end 38 of the drum acts to retard rotation of the drum and serves as a brake.

The supply of motive fluid to the rotors to effect their rotation will next be considered. It will be noted that pressure fluid, at times carrying with it lubricant, is supplied to the rotors from a suitable line 40 through a throttle valve 41. This valve 41 is controlled 75 by a usual controlling handle 42 and herein has a central chamber 43 adapted to supply motive fluid from the line alternatively to either of a plurality of spaced ports 44 and 45 from which the fluid is distributed by 80 means now to be described, to effect rotation of the rotors in opposite directions, the port 44 or 45 which is not being used as an inlet being used as an exhaust for a portion of the 85 used motive fluid and being adapted to be connected by grooves 46 or 47 to ports 48 or 49 communicating with the common exhaust passage 50. The passages 44 and 45 extend longitudinally through the shaft 3 and communicate respectively with annular grooves 90 52 and 53 spaced longitudinally of the shaft 3 and formed in the periphery thereof. Communicating with these annular grooves are series of radially extending passages 54 and 55 extending through the member carrying 95 the gear 11 and these passages communicate respectively with annular grooves 56 and 57 formed in the left hand end of the rotor casing (Fig. 2). From these grooves 56 and 57 there extend respectively passages 58 and 59 100 105 which open by suitable series of ports 60 and 61 into the rotor housing at points adjacent the mesh lines of the teeth of the spur gears 11 and 13 and 18 and 20. It will accordingly be understood that when the valve 110 41 is adjusted to supply motive fluid to the passageway 44 and to connect the passage 45 to the exhaust, relative rotation of the gearing will take place in one direction and will 115 effect rotation of the drum 1 in one direction, if the gear 20 be held stationary, whereas, a reversal of the position of the valve 41 will 120 effect a reverse rotation of the drum 1. For the purpose of taking care of the exhaust not discharged through ports 44 or 45, i. e. 125 125 the fluid trapped in the tooth pockets of rotors 13 and 18, I provide exhaust ports 62 formed in the bosses 12 on the wall of the housing 9 and opening into the interior of the same, and the exhaust fluid from these ports passes freely from the drum by ports 62'. It will be noted that ports 62 communicate with the tooth pockets at about the same relative time irrespective of the direction of rotation 130 of the rotors 13 and 18.

In order to admit lubricant to the teeth of the combined reduction gearing and motor, I provide a lubricant chamber 63 in the shaft 3 which chamber communicates by a passage 64 with an opening closed by a filling plug 65 and by a second passage 66 with a port 67 which is adapted to communicate in a neutral position of the valve with a pocket 70 formed therein and this pocket 70 is adapted when the valve is turned to its opposite positions 5 for effecting opposite rotations of the hoist drum, to communicate with passages 68 and 69 which lead downward and communicate with the chamber in which the valve 41 is disposed below the end of said valve. In order to permit the venting of the oil reservoir 63 I drill a vent port 71 through the valve in such manner that when the valve is in neutral position, this vent port, which at its 10 lower end communicates with the groove 70, is connected with a port 72 opening into the upper end of the passage 64. By reason of this connection it is possible to effectively permit the escape of air from the chamber 63. The arrangement of the ports in the valve 41 is such that when fluid is supplied to the port 44 the port 45 is connected by a groove 47 extending somewhat more than 180 degrees in the periphery of the valve with the 15 exhaust port 49 and that when fluid is supplied to the passage 45, a similar groove 46 connects the ports 44 and 48.

From the foregoing description, the mode of operation of this form of my hoisting mechanism will be, it is thought, readily apparent to those skilled in the art. It will be readily understood that it is not essential that the gear 11 be secured to the drum 1 and that the gear 20 be the one which by its locking to a stationary part, effects rotation of the drum, but instead the gear 20 may be rigidly secured to the drum and the gear 11 provided with means for alternatively permitting its free rotation or positive locking to check or effect rotation of the drum. In Fig. 12 I have shown a different means for locking the controlling gear, herein indicated by 11' and employ for this purpose a multiple disc clutch 74 arranged between a flange 75 secured to the gear 11' and a clutch applying sleeve 76 which is provided at its periphery with a worm wheel 77 and which is arranged in threaded engagement with the shaft 3 as indicated at 78. It will be noted that alternate disks are respectively held to the shaft 3 and the flange 75. A worm 79 operated by a handle 80 is journaled in the supporting arm member 7 and operates upon movement of the worm in opposite directions 20 by interaction of the threads 78 to apply and release the multiple disc clutch in such manner as to permit rotation of or to lock the gear 11'.

It will be also evident that as shown in Fig. 13, I may use an ordinary band brake 81 com-

prising a brake applying band 82 lined with frictional material 83 and cooperating with a flange 84 formed upon an extension of the gear 11' to effect locking and release of the gear 11' and to apply this brake band I use 70 a transverse reversely threaded bolt 85 cooperating with nuts 86 secured to the ends of the band 82 and by rotation of a handle 87 connected to the bolt 85, apply or release the 75 brake.

While I have in this application specifically described certain forms which my invention may assume in practice, it will be understood that these forms of the same are shown for purposes of illustration and that the invention may be modified and embodied in other forms without departing from its spirit or the scope of the appended claims. 80

What I claim as new and desire to secure by Letters Patent is:

1. In a hoist, a drum, driving means therefor comprising a plurality of intermeshing gears one of which is in fixed relation to said drum and another of which when locked or unlocked is adapted to control movement of 90 said drum, and means for supplying fluid to the teeth of said gears adjacent their points of mesh to effect relative rotation thereof.

2. In a hoisting mechanism, a drum, driving means therefor comprising a stationary 95 shaft, a pair of gears rotatable relative to said shaft, gearing cooperating with said first mentioned gearing, means for supplying pressure fluid to all of said gearing adjacent the lines of mesh of its constituent parts comprising passages extending laterally of said shaft, and means for locking at will one of said first mentioned gears relative to said shaft, the other of said first mentioned gears being non-rotatively connected with the 100 drum.

3. In a hoisting mechanism, a drum, a shaft, fixed and rotatable central gears thereon, one of said gears being fixedly connected to said drum, planet gears meshing with said 110 central gears, means for supplying pressure fluid axially of said shaft and central gears and longitudinally to a plurality of points along either side of the line of mesh of each central and planet gear, and means for releasing said fixed gear for rotation at will.

4. In a hoist, a drum, driving means therefor comprising a pair of coaxially arranged gears, gears meshing with each of said first mentioned gears respectively and revolving in 120 an orbit defined by the periphery of said first mentioned gears, said second mentioned gears being fixed for rotation in unison, means for supplying fluid under pressure between the meshing teeth of said first and second mentioned sets of gears, means directly connecting one of said first mentioned gears to said drum whereby relative rotation therebetween is prevented, and means for holding the other 125 thereof stationary or permitting it to rotate 130

about its own axis at will, said last mentioned means being movable to effect braking of said drum.

5. In a hoist, a drum, a motor including a housing disposed therein and rotatable relative thereto, a plurality of coaxial gears mounted in said housing and rotatable on running of said motor and adapted to rotate about an axis parallel to the axis of said drum but spaced therefrom, said axis traversing an orbit as said drum is winding and while fully operative, a member carrying a gear with which one of said first mentioned gears is adapted to mesh during rotation of said drum, means associated with the remainder of said first mentioned gears to drive said drum, means for operatively supporting all of the above mentioned elements, and means for locking or releasing said member at will.

10. 6. In a hoisting mechanism, a drum, a motor within said drum comprising means providing a plurality of rotor chambers having rotors therein, said rotors rotating on their own axes and said chamber providing means rotating on the same axis as the drum while the drum is rotating during winding, and means comprising a manually controllable gear and a gear meshing therewith and traversing an orbit as said drum rotates for causing said drum to rotate or remain stationary.

15. 7. In a hoist, a drum, and driving means therefor including a pressure fluid motor comprising a housing having disposed therein gearing each element of which acts both as a power generating motor rotor and a reduction gear element, and pressure fluid supply and exhaust means therefor, one element of said gearing having a portion within and operatively connected to said drum, and means for locking or releasing another element of said gearing.

20. 8. In a hoisting mechanism, driving means for a drum including a motor comprising a housing having disposed therein gearing each element of which acts both as a power generating motor rotor and a reduction gear element, one element of said gearing being directly non-rotatably connected to the drum, motive fluid supply and exhaust connections therefor arranged coaxially thereof, and means for controlling said gearing comprising means for locking or releasing one element thereof.

25. 9. A hoisting mechanism comprising a winding drum and a motor disposed about a common axis, said drum being supported for rotation but fixed against axial movement, and means disposed within said drum and including an element movable along said axis to bring said motor and drum in relation so as to rotate the latter by said motor, or to terminate said relation.

30. 10. A hoisting mechanism comprising a winding drum and a motor having a common

axis, means including an element movable along said axis to connect said drum and motor in relation so as to rotate the drum by the motor, said element being immovable during said connection and rotatable actuating means for said element.

35. 11. A hoisting mechanism comprising a winding drum and a motor having a common axis, means having a portion thereof disposed within said drum including an element movable along said axis to connect said drum and motor in relation so as to rotate the drum by said motor, and actuating means for said element having members movable in opposite directions.

40. 12. A hoisting mechanism comprising a winding drum, a shaft extending therethrough and substantially concentric to said drum, a motor having a power driven element, means whereby said drum may be driven by said power driven element including power control mechanism disposed within said drum and carried by said shaft whereby said motor may be connected in relation to said drum so as to rotate the drum by said motor, and means for controlling said power control mechanism from the exterior of said drum.

45. 13. A hoist comprising a winding drum, a power driven element, and means whereby said drum may be driven by said power driven element including releasable power control mechanism having a portion disposed within said drum and immovable when the same is operative to effect drum drive.

50. 14. A hoist comprising a winding drum, a motor having a power driven element, and means whereby said drum may be driven by said element including power control mechanism disposed within said drum for connecting said drum and power driven element in relation so as to rotate the drum by said motor, said power control mechanism having a member movable when said power control mechanism is inoperative to effect drum drive and stationary during drum driving.

55. 15. A hoisting mechanism comprising a winding drum, means whereby the same may be driven including power transmitting control mechanism disposed therein, and means for operating said control mechanism from the exterior of the drum.

60. 16. A hoist comprising a winding drum, and means whereby the same may be driven and controlled including a brake having a portion disposed within said drum and immovable when the drum is winding.

65. 17. A hoist comprising a winding drum, and means whereby the same may be driven including a brake disposed within said drum and an element movable when inoperative to effect drum drive.

70. 18. A hoisting mechanism comprising a winding drum, means whereby the same may be driven including a brake disposed there-

in, and means for operating the same from the exterior of the drum.

19. The combination set forth in claim 6 further characterized in that said manually controllable gear has controlling means including frictional controlling means.

20. The combination set forth in claim 6 further characterized in that the manually controllable gear is provided with means for 10 releasably holding the same against rotation.

21. In a hoisting mechanism, a drum, and driving means therefor including intermeshing rotors whose axes lie in a common plane, supporting means for said rotors providing 15 for rotation of one of the same orbitally about the other and rotation of the latter upon a fixed axis, means for supplying fluid selectively to said rotors at either side of a plane including their axes and adjacent the 20 mesh line between the rotors to effect operation of the motor in opposite directions and for conducting away exhaust motive fluid when the motor is running in either direction, means for selectively holding or releas- 25 ing the rotor which is supported for rotation on a fixed axis, and means including a gear coaxial with the drum and a gear meshing with said last mentioned gear and rotatable coaxially with said orbitally rotating 30 rotor for driving the drum.

22. A hoist comprising a winding drum, and means whereby the same may be driven or braked including an element within said drum movable in opposite directions to effect 35 drum drive and to brake drum rotation.

In testimony whereof I affix my signature.

ELMER G. GARTIN.
